UNITED STATES PATENT OFFICE.

GUY L. KEENE, OF BROCKTON, MASSACHUSETTS, ASSIGNOR TO UNITED SHOE MACHINERY CORPORATION, OF PATERSON, NEW JERSEY, A CORPORATION OF NEW JERSEY.

MARKING MACHINE.

Application filed September 25, 1924. Serial No. 739,937.

To all whom it may concern:

Be it known that I, GUY L. KEENE, a citizen of the United States, residing at Brockton, in the county of Plymouth and Commonwealth of Massachusetts, have invented 5 certain Improvements in Marking Machines, of which the following description, in connection with the accompanying drawings, is a specification, like reference characters on 10 the drawings indicating like parts in the several figures.

This invention relates to marking machines and more particularly to the type-carrying heads thereof.

15 Marking machines for numbering and labeling shoe parts, clothing and the like are commonly arranged to apply a row of characters, which must be changed frequently, combined with other printed matter such as 20 names or trade-marks, which need to be changed less frequently. An arrangement of this character is illustrated in United States Letters Patent No. 1,170,490, granted February 1, 1916, on the application of Edward B. Parkhurst, in which the marking 25 head is provided with a plurality of rotatable type-wheels bearing numbers or letters adapted to be adjusted at will together with a type-plate, sometimes called a "trade- 30 plate", upon which other printed matter has been engraved. As shown in said patent, the type-plate is detachable and retained in position upon the marking head by jaws, one of which is pivoted and resiliently held 35 in clamping position so that it may be released and the plate removed at will. It is desirable that the characters upon the type-plate shall be as close as possible to the characters on the type-wheels when the impression 40 is made so that the whole imprint may occupy as little space as possible and, in the case of shoes, may all be near the top of the lining of the shoe. On the other hand, rotation of the type-wheels without interference 45 with the edges of the type-plate upon which the fixed rows of characters appear requires that the slot through which the characters on the type-wheels pass shall be of substantial size. In order to attain as 50 compact an arrangement as is desirable, the name-plates are commonly arranged with only a narrow slot, and the rows of characters are disposed along the sides of this slot. The width of this slot may be only so much 55 as is necessary to admit a single row of type

on the type-wheels. In view of this arrangement, the operator, when she wishes to turn the type-wheels, must open the jaws and partially or wholly remove the name-plate. In the arrangement disclosed in the Parkhurst patent, the opening of the jaws allows the plate to drop out. The common practice is for the operator to catch the plate in her hand and then after setting the type-wheels, return the plate to position and lock it in position within the jaws. This soils 60 the operator's hand and is, of course, inconvenient and time-consuming.

Accordingly an object of the invention is to provide a retainer for the type-plate of a 70 marking head, which will allow the partial separation of the type-plate from the type-wheels when the plate is released without allowing it wholly to drop out of the jaws.

In the illustrated machine, in accordance 75 with features of the invention, a projecting stud is inserted in one side of the frame of the marking head and a retaining bail pivotally connected to the ends of the type-plate is passed around the ends and side of 80 the marking head and disposed above the projecting stud. The dimensions of the bail and adjacent parts are such that when the plate is released by the operation of the movable jaw, it will tilt away from the type-wheels sufficiently to allow their adjustment 85 without completely removing the plate from the marking head. Preferably the edge of the type-plate at the side and above the points of attachment of the bail is chamfered. By relieving this corner of the plate, as by chamfering, the operator is able completely to remove the plate from the marking head by turning it around the fixed jaw 90 of the marking head until it is in a position to allow it to be moved laterally and removed from the head together with the bail.

For a more complete understanding of the invention, reference may be had to the following specification taken in connection 100 with the accompanying drawing in which:

Fig. 1 is a front elevation of a marking head embodying the invention;

Fig. 2 is a side elevation partly in section showing the type-plate held in position by 105 the jaws; and

Fig. 3 is a similar elevation showing the type-plate released from the movable jaw and supported by the bail.

Marking machines of the type under con- 110

sideration are commonly provided with a work support and a reciprocating or oscillating mechanism adapted to carry the type-carrying marking head into and out of contact with the work. For the purpose of illustration, there has been shown a type-head having a frame 10 within which are supported type-wheels 12, 14, 16, etc., capable of being turned on or with a shaft 18 frictionally engaging said wheels. The shaft 18 is provided with an operating handle 20. Latches 22 having finger pieces 24 are provided for each individual type-wheel, and the latches normally hold the type-wheels in fixed position but may be released by depressing the finger pieces 24 to allow the setting of one or more type-wheels by rotation of the operating handle 20.

In order that the machine may be enabled to print more than the characters provided upon the type-wheels, the frame 10 of the marking head is provided with jaws 26 and 28 which are slotted to engage the edges of a type-plate 30. The slotted jaw 28 is displaceably supported upon a bell crank lever 32 provided with a finger piece 34 and normally held in closed position by means of a spring-operated plunger 36. The type-plate 30 may take any one of a large variety of forms and is herein illustrated as provided with a detachable electrotype 38 and a row of interchangeable type-members 40 which are placed adjacent to the edges of a slot in said plate which receives that row 42 of type on the type-wheels which is in operative position for marking the work. The arrangement of the type-plate is such that the marking surfaces of the removable type-members 40, the row of type 42, and the electrotype 38 are flush with one another.

To allow the partial separation of the type-plate from the type-head without fully releasing it when the movable jaw 28 is opened, a plate-retainer having the form of a bail 43, preferably constructed of spring wire, is provided. The inturned ends of the bail 43 are entered in sockets 44 at the ends of the type-plate adjacent to the edge which is received within the groove of the fixed jaw 26, and then the loop of the bail is passed around the ends and across the side of the frame of the marking head above a stud 46. The retaining bail is so adjusted and designed that when the jaw 28 is opened, the plate will be partially released and will drop to the position illustrated in Fig. 3 in which it is retained, supported by the bail and by frictional engagement of the upper surface of the plate with the lower surface of the frame of the marking head and by engagement of the lateral edge of the plate with the lateral face of the fixed jaw 26. By relieving the upper edge 47 of the type-plate, as by chamfering, the operator is enabled completely to remove the type-plate

from the marking head by turning it around the points of attachment of the ends of the bail and the corner 48 of the jaw 26 until it has been rotated through substantially 180 degrees, whereupon it may be moved laterally to remove it from the marking head. It will be noted also that the lower corner 50 of the grooved movable jaw 28 is slightly beveled so that the type-plate may be pressed into the groove of the movable jaw 28 without necessarily depressing the finger piece 24 thereof.

In using the machine, whenever the operator wishes to change the position of the type-wheels, she will first depress the finger piece 34 and allow the type-plate to drop into the position shown in Fig. 3 where it will be held by the action of the retaining bail 43. She will then depress the particular finger piece 24 corresponding to the type-wheel which it is desired to rotate and by turning the operating handle 20 will bring into position in the row of types 42 the particular character which it is desired to use. Preferably she will then replace the type-plate within the jaw 28, but if this action of replacement is forgotten, the plate will be pushed into position and the jaw 28 will snap over the edge of the plate when the marking head is depressed.

Having thus described the invention, what I claim as new and desire to secure by Letters Patent of the United States is:

1. In a type-head, type-carriers supported in said head, a type-plate adapted to be brought into co-operative relation with a row of characters on said type-carriers, a jaw member co-operating with one edge of said type-plate to position it upon the type-head, and a retaining member co-operating with the last-mentioned edge of the type-plate and the type-head, said retaining member and said jaw member being constructed and arranged to support said type-plate in a position tilted away from the type-carriers so that the type-carriers may be adjusted to change the row of characters in printing position.

2. In a type-head, type-carriers supported in said head, a type-plate adapted to be brought into co-operative relation to a row of characters on said type-carriers, a jaw member co-operating with one edge of said type-plate to position it upon the type-head, a retaining member co-operating with the last-mentioned edge of the type-plate and the type-head, said retaining member and said jaw member being constructed and arranged to support said type-plate in a position separated from the type-carriers so that the type-carriers may be adjusted to change the row of characters in printing position, and means on said type-head co-operating with the other edge of the type-plate to retain the type-plate in printing position.

with its printing surface substantially flush with the row of characters on the type-carrier.

3. In a type-head, a supporting surface, a fixed jaw adjacent to one side of said surface, a type-plate, displaceable means acting in conjunction with said fixed jaw to retain the type-plate normally against said supporting surface and allowing it to drop away from said surface when displaced, and other means to retain said plate in a position slightly separated from the supporting surface when released from the displaceable means.

15. 4. In a type-head, a supporting surface, a fixed jaw adjacent to one side of said surface, a type-plate, displaceable means acting in conjunction with said fixed jaw to retain the type-plate normally against said supporting surface and allowing it to drop away from said surface when displaced, and other means acting in conjunction with said fixed jaw to retain said plate in a position slightly separated from the supporting surface when released from the displaceable means.

30. 5. In a type-head, a type-plate resting against a supporting surface of said head, a frame provided with a lateral recess adapted to receive and support the lateral edge of the type-plate, a projection on the frame, and a retaining bail passing over said fixed projection pivotally secured to the ends of the type-plate, said bail being constructed and arranged to support the type-plate in engagement with said recess, and in a position slightly separated from the plate-supporting surface upon the type-head.

40. 6. In a type-head, a frame, one or more type-wheels rotatably mounted within said frame, jaws upon said frame one of which is movable, a type-plate having characters flush with the character upon the type-wheel and held in position by said jaws, and a retaining bail engaging the edges of the type-plate away from the movable jaw and passing over a projecting part of the type-head, arranged to allow the type-plate to be separated sufficiently from the type-head to allow rotational adjustment of the type-wheel without wholly removing the type-plate from the type-head.

50. 7. In a type-head, a plurality of type-

wheels rotatably mounted for adjustment within said head to bring a row of characters in position adjacent to the end of the head for marking the work, a slotted type-plate disposed on the head so that the row of characters on the type-wheels passes through the slot of the type-plate, said plate having characters flush with the row of characters on the wheel, said head being provided with a fixed jaw and a movable jaw arranged to receive and retain the edges of said type-plate, and a retaining bail passing over a fixed projection upon the type-head with its ends bent and attached to the ends of the type-plate adjacent to the fixed jaw, said bail being constructed and arranged to support the type-plate in a position sufficiently separated from the type-wheels, when the type-plate has been released by opening the movable jaw, so that the type-plate will not interfere with the adjustment of the type-wheels.

75. 8. In a type-head, a frame provided with a grooved jaw, an opposed movable grooved jaw mounted on said frame, a plurality of type-wheels rotatably supported within said frame for adjustment to bring a row of characters into marking position between said jaws, a slotted type-plate positioned in said jaws with the row of characters on the type-wheels projecting through the slot of the plate and flush with the characters on the plate, sockets in the ends of the type-plate adjacent to the fixed jaw, and a retaining bail fastened over a projecting upon the frame of the marking head with its ends entering the sockets of the type-plate, constructed and arranged to allow the type-plate to be separated sufficiently from the type-wheels to allow their adjustment and arranged to support the type-plate when released by the opening of the movable jaw to prevent it from dropping out of the machine, the upper edge of said type-plate adjacent to the fixed jaw being relieved sufficiently to allow the rotation of the type-plate around the points of attachment of the bail to permit its removal from and insertion in the fixed jaw of the type-head.

90. In testimony whereof I have signed my name to this specification.

GUY L. KEENE.
